(57) **CLAIM**

The ornamental design of a dot-type laser level as shown and described.

DESCRIPTION

FIG. 1 is a first isometric view of a dot-type laser level incorporating our new design;

FIG. 2 is a second isometric view thereof;

FIG. 3 is a first side elevation view thereof;

FIG. 4 is a second side elevation view thereof;

FIG. 5 is a first end elevation view thereof;

FIG. 6 is a second end elevation view thereof;

FIG. 7 is a top plan view thereof; and,

FIG. 8 is a bottom plan view thereof, wherein the portions shown in phantom form no part of the claimed design.

1 Claim, 8 Drawing Sheets
